UNITED STATES PATENT OFFICE

THOMAS DOWSLEY KENNEDY AND JAMES JOSEPH KEON, OF OWEN SOUND, ONTARIO, CANADA, ASSIGNEES TO WILLIAM KENNEDY & SONS, LIMITED, OF OWEN SOUND, ONTARIO, CANADA

STOP LOG WINCH

Application filed February 14, 1931. Serial No. 515,778.

This invention relates to apparatus for raising, lowering and piling stop logs used in stop log dams and our object is to provide simple apparatus of this character in which the members of the ram, for raising the logs from and lowering them into the stop log checks in adjacent piers of the dam, are so arranged that the tendency of the current to carry them out of position for engagement with the logs at the bottom of the checks will be overcome. A further object is to provide simple means for transferring the logs from the ram to a log piling device and vice versa. A still further object is to provide a point of weakness in the mechanism for operating and guiding the ram members whereby an inexpensive and readily replaced part will be broken should the operating mechanism be clogged by ice or floating pieces of timber picked up by it.

We attain our objects by diverging the ram members so that as the members are moved downwardly their lower ends are spread apart to bring them closer to the inner walls of the checks in the piers of the dam. The apparatus includes a frame which spans the space between adjacent piers, the ram members being slidably mounted on suitable guides located at opposite ends of the frame. The ram members may be centrally located, or be located off center upstream or downstream, relative to the upstream and downstream sides of the frame to suit conditions on the dam. The logs removed from the dam are piled on the piers by a log piling conveyor which is located above the main members of the said frame. To transfer the logs from the ram to the log piling conveyor, we provide a log transfer conveyor which is mounted on the underside of the said main members. The ram is operated by means of a rack and pinion, the rack being carried by the ram and held in operative position by means of a thrust roller engaging the side of the ram remote from the pinion. The

thrust roller is carried by two arms pivoted on a casting which also carries the bearings for the pinion. A bolt secures each pivoted arm to the casting and either bolt or both of them are adapted to break should the thrust on the roller exceed a predetermined maximum.

The constructions are hereinafter more fully described and are illustrated in the accompanying drawings in which

Fig. 1 is a cross-section of two adjacent piers of a dam showing our apparatus in position thereon;

Fig. 2 a plan view on a smaller scale of the parts shown in Fig. 1 and showing more of the dam construction;

Fig. 3 a section on the line 3—3 in Fig. 1;

Fig. 4 a detail, partly in section, of a lower ram guide;

Fig. 5 a cross-sectional detail of one end of a stop log showing the ram engaged therewith;

Fig. 6 a plan view of one end of a stop log; and

Fig. 7 a detail in plan of an upper ram guide, the ram member being shown in cross-section.

In the drawings like numerals of reference indicate corresponding parts in the different figures.

A stop log dam comprises two or more piers 1 which are provided with checks 2 for receiving the opposite ends of stop logs 3 which span the space between adjacent piers. The logs are raised from and lowered into the checks by means of a ram comprising two members 4 having detachable connections with a log. Preferably these connections comprise an undercut slot 5 at each end of a log in its upper face and these slots may be formed by recessing the logs and covering the recesses by plates or irons 5^a having slits formed therein. An "arrow" 6 or inverted T-shaped rod is carried by each member 4 and these arrows are adapted to be passed

75

80

85

90

through the slits or spaces in the plates at the opposite ends of a log so that when each arrow is turned one-quarter revolution in its recess it will engage the underside of its overlying plate. As this arrangement for forming a detachable connection between a ram and a stop log is well known in the art, the details of construction for mounting and turning the arrows on the ram members need not be described.

The ram members 4 are vertically slidable on the frame 10 of the winch apparatus and in the checks 2 for the purpose of guiding the arrows 6 into the slits in the log plates 5.

Much difficulty is experienced in preventing the rams 4 from working out of the checks 2 especially when the rams are being lowered for engagement with the lowermost log because the water flowing over the log enters the checks and tends to dislodge the rams therefrom. In other words eddying currents are set up between the inner walls 2^a of the checks and the sides of the ram members 4 adjacent thereto and these currents tend to

move the rams out of the checks and thus move the arrows out of position for engagement with the slits in the log plates 5^a. To overcome this difficulty we provide means for spreading the lower ends of the ram members 4 apart so that the lower ends will tend to engage the inner walls 2^a of the checks 2. The ram members are vertically slidable in upper and lower guides 7, 8, the lower guides 8 being carried on the main members 9 of the

frame 10 of the apparatus and located at the opposite ends of the said members 9. The upper guides 7 are adjustably mounted for lateral displacement on towers 10^a which are suitably carried on the members 9. Each of

the guides 7 comprises an annular slide 7^a, see Figs. 7 and 1, adapted to slidably receive a ram member 4. The slide is provided with flanges 7^b which rest on supporting blocks 7^c and are connected therewith by bolt and slot

connections 7^d. The blocks 7^c are provided with lugs through which are threaded adjusting screws 7^e for moving the slides away from and towards one another. By loosening the inner screws 7^e away from the inner sides of the slides 7^a and tightening the outer screws against both slides, the latter, and thus the upper ends of the ram members 4, will be moved towards one another. This movement of the ram members causes them to rock in

their lower guides 8 and thus the lower ends of the members will be swung away from one another and towards the inner walls 2^a of the checks. From this construction it is obvious that the members 4 may be so diverged that

their lower ends may be brought into contact with the inner walls 2^a at any desired point beneath the water line. It is also obvious that the farther the ram members 4 are lowered below the above mentioned point, the tighter they will contact with the inner walls 2^a and

thus any springiness in the members, as the distance between the lower ends thereof and the guides 8 increases, is compensated.

The guides 8 are located substantially centrally between the front and rear sides and at opposite ends of the main members 9 of the frame 10 of the apparatus. These members 9 span the space between adjacent piers 1 and if more than two piers be used in one dam the members will be carried on trucks which run on tracks so that the one apparatus may be used to raise or lower the logs between any two of the piers. It will thus be seen that the main frame members 9 limit the upward movement of the logs by the ram members 4 and also prevent the usual log piling conveyor 11 from engaging the raised log supported on the ram. Heretofore it has been the general practice to place a skid formed of crowbars or pieces of timber under the log, when it is raised by the ram member above the top of the piers 1, so that the log may be slid laterally of the frame members 9 to a position in which it may be engaged by the conveyor 11. To overcome this objectionable feature of manually skidding the logs to and from the ram, we provide a log transferring conveyor 12 which comprises tracks 13 arranged transversely of the frame members 9 and secured to the underside thereof between the ram members 4. On the tracks are mounted trolleys 14 from which are suspended any suitable stirrups 15 adapted to be disconnected intermediate their ends or at their connection with the trolleys so that they may be passed around the underside of the log and re-connected while the latter is being supported in its raised position by the ram members 4. The ram is then lowered until the log is supported by the stirrups 15. The arrows 6 are then turned one-quarter revolution to release the ram members 4 and the latter are raised to clear the log which is now free to be moved laterally by the transfer conveyor 12. The latter is thus adapted to move a log from beneath the main frame members 9 and position it for engagement by the log piling conveyor 11 which is mounted above the members 9 so that it may raise the logs to a sufficient height to pile them on top of the piers. The conveyor 12 transfers the logs from the piling conveyor 11 to the ram members 4 when the logs are being inserted in the checks 2.

The guides 8 are provided with bearings 16 in which pinions 17, which mesh with racks 18 carried by the ram members 4, are journaled. The sides of the members 4 remote from the pinions are engaged by thrust rollers 19 each of which is journalled in pivoted arms 20 which are pivoted at 23 in the guides 8. Each of the thrust rollers 19 is held in its operative position by means of bolts 21 which connect the arms 20 with lugs 22 cast on the guides. These parts are so designed that

the bolts 21 will break should the thrust on the rollers 19 exceed a predetermined maximum. As a supply of bolts which are inexpensive may be readily carried and a broken bolt may be readily replaced, any damage, caused by ice formation on the racks or by either of them picking up foreign matter such as floating pieces of wood, will not be serious.

Any suitable means may be provided to limit the swinging movement of the arms 20 away from the ram members 4 when the bolts 21 break so that the ram members will be prevented from dropping by gravity. That is to say, while the breakage of the bolts will permit the ram members and thus the racks 18 carried thereby to move relative to the pinions 17, this movement is limited so that the teeth on the racks will not be demeshed from the teeth on the pinions. To permit a thrust roller 19 to swing axially if only one of its bolts 21 should break, we provide a swivel connection between the arms 20 and their pivots 23. This connection may be formed by tapering or countersinking the hole through each arm from the opposite sides thereof, whereby the contact with the pivot 23 will be substantially midway between the sides of the arm and the latter will be free to rock on its pivot.

The pinions 17, see Figs. 4, 1 and 2, may be driven in any suitable manner from any suitable source of power to raise or lower the rams 4.

What we claim as our invention is:

1. Apparatus for raising stop logs out of checks in a stop log dam including a ram comprising two members vertically movable in the checks for engagement with the opposite ends of a stop log, the said members being mounted in divergent positions whereby their lower ends spread towards the inner walls of the checks while the members are being lowered relative thereto.

2. Apparatus for raising stop logs out of checks in a stop log dam including a ram comprising two members vertically movable in the checks for engagement with the opposite ends of a stop log; and a set of upper and lower guides for slidably receiving each of the members, the guides of each set being positioned relative to one another to cause the lower ends of the members to be spread away from one another and towards the inner walls of the checks while the members are being lowered.

3. Apparatus for raising stop logs out of checks in a stop log dam including a ram comprising two members vertically movable in the checks for engagement with the opposite ends of a stop log; and a set of upper and lower guides for slidably receiving each of the members, the guides being adjustable relative to one another for diverging the mem-

bers to spread their lower ends apart while they are being lowered.

4. Apparatus for raising, lowering and piling stop logs used in a stop log dam including a vertically movable ram for engaging a stop log; a log piling conveyor movable laterally of the ram; and a log transferring conveyor movable transversely of the ram and adapted to convey the logs from the ram to a position in which they may be engaged by the piling conveyor.

5. Apparatus for raising, lowering and piling stop logs used in a stop log dam including a frame adapted to span the space between adjacent piers of the dam; a vertically movable ram carried by the frame for engaging a stop log to raise it from and lower it into the dam; a log piling conveyor mounted on the apparatus above the said frame to move laterally of the ram; and a log transferring conveyor mounted on the underside of the said frame to move transversely thereof for conveying logs from the ram to a position in which they may be engaged by the piling conveyor and vice versa.

6. Apparatus for raising and lowering stop logs used in a stop log dam including a vertically movable ram for engaging a stop log to raise it from and lower it into the dam; and a conveyor carried by the apparatus for conveying a log laterally from and to the ram.

7. Apparatus for raising, lowering and piling stop logs used in a stop log dam including a frame adapted to span the space between adjacent piers of the dam; a vertically movable ram carried by the frame for engaging a stop log to raise it from and lower it into the dam; and a conveyor mounted on the underside of the said frame to move transversely thereof for conveying logs to and from the ram.

8. Apparatus for raising and lowering stop logs used in a stop log dam including a vertically movable ram for engaging a stop log to raise it from and lower it into the dam; and a conveyor carried by the apparatus including detachable stirrups adapted for conveying a log laterally from and to the ram.

9. Apparatus for raising, lowering and piling stop logs used in a stop log dam including a frame adapted to span the space between adjacent piers of the dam; a vertically movable ram carried by the frame for engaging a stop log to raise it from or lower it into the dam; a track secured to the underside of the frame and projecting laterally therefrom; and a trolley mounted on the track and provided with a carrier for conveying logs to and from the ram.

10. Apparatus for raising and lowering stop logs used in a stop log dam including a ram for engagement with a stop log; a rack carried by the ram; a pinion meshed with the rack; a guide for the ram comprising

a casting in which the pinion is journalled; an arm pivoted on the casting; a thrust roll journalled on the arm for engaging the side of the ram remote from the rack; and a bolt arranged transversely relative to the axis of the pivoted connection for connecting the arm and the casting, to form a point of weakness.

Signed at the city of Owen Sound, Canada,
